(57) **CLAIM**

The ornamental design for a valve tamper shield and valve assembly, as shown and described.

DESCRIPTION

FIG. 1 is a front perspective view of a valve tamper shield and valve assembly according to a first embodiment of the present invention;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof.

FIG. 8 is a front perspective view of a valve tamper shield and valve assembly according to a second embodiment of the present invention;

FIG. 9 is a top plan view thereof;

FIG. 10 is a bottom plan view thereof;

FIG. 11 is a right-side elevation view;

FIG. 12 is a left side elevation view thereof;

FIG. 13 is a front elevation view thereof; and,

FIG. 14 is a rear elevation view thereof.

The broken lines shown in the drawings depict portions of the valve tamper shield and valve assembly and environment that form no part of the claimed design.
